UNITED STATES PATENT OFFICE.

JOSEPH FRANKLYN TURNER, OF DANVILLE, VIRGINIA.

DENTAL FULCRUM-FORCEPS.

1,147,580.

Specification of Letters Patent. Patented July 20, 1915.

Application filed November 10, 1914. Serial No. 871,393.

To all whom it may concern:

Be it known that I, JOSEPH FRANKLYN TURNER, a citizen of the United States, residing at Danville, in the county of Pennsylvania and State of Virginia, have invented new and useful Improvements in Dental Fulcrum-Forceps, of which the following is a specification.

This invention relates to detachable fulcrum forceps for dental operations and particularly to a cross-bar providing means for ready attachment and detachment of a plurality of forceps of different types.

The improvement comprises essentially a cross-bar and forceps, the cross-bar having a socket means embodied therewith to receive a ball connected to the forceps at a distance from the working extremity of the latter, the ball being held in the socket of the cross-bar by a readily closing and opening device also disposed on the cross-bar.

The improvement embodying the components just specified is especially intended for operations on impacted or uninterrupted lower third molars and a plurality of forceps is adapted to be used with the cross-bar so that one pair of forceps, for instance, of a proper character may be applied to the cross-bar for use in the occlusal surface of the third molar when abutted against the distal surface of the second molar, or when the third molar is only partially erupted; or forceps intended for simpler operations or cases may be detachably connected to the cross-bar or an elevator forceps may be associated with the cross-bar for operation on roots. The cross-bar is not limited to the use therewith of any precise form of forceps, but the cross-bar serves as a means for receiving a part of a fulcrum device carried by various forceps to permit the latter to be moved in vertical and opposite sidewise directions to accommodate various operations.

The primary object of the invention is to provide for the concentration of considerable force to lift a tooth from its socket by a comparatively simple pressure operation in a downward direction on the handles of the forceps when performing an extraction, the forceps used being permitted to have a free motion in all directions.

The invention consists in the construction and arrangement of the several parts which

will be more fully hereinafter described and claimed.

In the drawing: Figure 1 is a perspective view of a cross-bar or rest embodying the features of the invention and showing a pair of flat beaked forceps operatively associated therewith. Fig. 2 is an enlarged transverse vertical section through the cross-bar or rest and a portion of the forceps shown by Fig. 1 and particularly illustrating the ball and socket joint components in assembled relation. Fig. 3 is a transverse vertical section taken in the plane of the line 3—3, Fig. 1. Fig. 4 is a detail perspective view of a portion of a round tapering beaked forceps. Fig. 5 is a detail perspective view of a portion of an elevator forceps embodying a part of the features of the invention. Fig. 6 is a top plan view of the fulcrum supporting rest or cross-bar with which the several forceps may be detachably assembled.

The essential feature of the invention consists of a supporting rest or cross-bar adapted to be disposed on the teeth in proper position in any manner found advantageous in pursuing the operation to be performed and provided with means for permitting different forms of forceps to be detachably assembled therewith. This cross-bar comprises two sections or members 5 and 6, preferably of drop forged steel, the section 6 being movably mounted on the top section 5 through the medium of a fulcrum pin 7 extending therethrough to one end and into the section 5. The section or member 5 has a lower recess 8 in which is secured a semi-hard piece of rubber 9 for the protection of the teeth on which the cross-bar or rest as a whole is disposed. The rubber piece 9, as clearly shown by Figs. 2 and 3, has side flanges 10 embracing portions of the opposite sides of the section or member 5, and the ends of the section or member 5 slightly depend below the under side of the rubber piece 9, as at 11, to provide terminal guards. The section or member 5 near the pivoted or fulcrumed end of the section or member 6 is formed with a socket 12 and is also constructed adjacent to said socket with a boss 13 having inner inclined walls 14, the socket in the section or member 5 being continued upwardly into and through the center of the boss, as at 15. The walls 14 converge toward the continuation of the

socket in the boss and form stop walls for the movable section or member 6 which has a recess 16 of the same contour as the inner portion of the boss to permit it to close 5 snugly against the boss, the socket also being continued upwardly through the section or member 6, as at 17, and with the continuation of the socket through the boss forming a throat for the socket 12. The section or 10 member 6 constitutes a cover or closure as well as a keeper, and adjacent to its free end a slot 18 is formed therein and extends through one side edge to permit the said section or member 6 to freely move over and 15 clear a pin 19 rotatably held in an adjacent portion of the section or member 5 below, the said pin having a hooked or angular head 20 which is adapted to be turned over and bear upon the upper surface of the section 20 6 adjacent to the slot 18. It will therefore be seen that the pin 19 and its head 20 form a catch or a lock for holding the section or member 6 in fixed position on the section or member 5. The catch or locking 25 means comprising the pin 19 and head 20 may be readily turned to lock the section or member 6 on the section or member 5 or to release said section 6 as may be desired.

The forceps 21 shown by Figs. 1 and 2 30 have flat beaks 22 adapted for simple operations, and the forceps 23, shown by Fig. 4, have round tapering beaks 24. The forceps 25, shown by Fig. 5, are of the elevator type and are intended for roots, and are 35 provided with a shank 26 which is gradually reduced toward and secured to and formed as a part of an elevator head 27. All of the forceps shown are preferably embodied in the complement or special equipment comprising the improved supporting 40 rest or cross-bar. It will be understood, however, that other forceps may be employed with the said supporting rest or cross-bar. All of the forceps shown are 45 provided with a ball 28 adapted to be inserted in the socket 12 by first releasing the cover or closure formed by the section or member 6 and then moving the latter into normal position over the top portion of the 50 section or member 5 and securing the said cover or closure against movement as hereinbefore explained. Each of the balls 28 is formed with a neck 29 of sufficient length to permit the forceps to freely move in dif- 55 ferent directions on the supporting rest or cross-bar when the several forceps are associated with the said rest or cross-bar. The neck 29 in the forceps shown by Figs. 1, 2 and 4 is continuous with the fulcrum pin 30 60 of the jaws or beaks and whereby the structure is very much simplified for the reason that by a slight addition to the fulcrum pin or the provision of the neck 29 and ball 28 as a part thereof the necessity of a separate 65 construction of ball and neck is obviated.

From the foregoing it will be seen that either one of the pairs of forceps may be quickly assembled in connection with the supporting rest or cross-bar, and the latter is placed on the molar teeth and the beaks of the forceps carried by the rest or bar are forced to place on the tooth. By pressing downwardly on the handles of the applied forceps the tooth to be extracted is given an upward and backward force and the tooth 70 lifted from its socket, the rest or bar acting as a fulcrum in this operation and the ball and socket connection giving free motion to the forceps in all directions.

The forceps are all to be made of steel 80 except the handles of the elevator forceps, which are preferably formed of hard wood and set in and riveted.

It will be found that by the use of the improvement as hereinbefore described the 85 operation of extraction in connection with molar teeth and especially impacted or unerupted lower third molars will be exceptionally advantageous and practicable, the operation of extraction by the use of the improvement being materially simplified and possible with a comparatively small amount of applied force and without injury to the 90 remaining teeth or the jaw bones.

It will be understood that changes in the 95 proportions, dimensions and minor details may be resorted to to accommodate various applications and uses without departing from the spirit of the invention.

What is claimed is:

1. The combination with forceps having a 100 projection with a ball, of a supporting rest having a socket to receive said ball, and a movable cover member to hold the ball detachably assembled with the rest.

2. The combination with forceps having a ball fixed thereto, of a supporting rest having a socket to detachably receive and hold the ball and forceps in movable connected 105 relation to the rest.

3. The combination with forceps having a ball fixed thereto, of a supporting rest comprising a socket member to receive the ball, and a second member movably mounted on the socket member to hold the ball and forceps in movable connected relation to the rest, the socket member being provided with locking means to engage the movably mounted second member.

4. The combination with forceps having a ball fixed thereto, of a supporting rest comprising a socket member to receive and hold said ball and having a lower rubber strip, located above the lower portions of the opposite extremities of the said socket member and provided with side flanges embracing the opposite sides of the said member, and a second member movably mounted on the socket member to hold the ball and forceps in movable connected relation to the rest,

the socket member being provided with locking means to engage the movably mounted second member.

5. A supporting rest adapted to be disposed and rest on the teeth and comprising a socket member and an upper laterally movable retaining member mounted on the socket member, and forceps having a ball held thereby at a distance from the working 10 extremity thereof to detachably fit into the socket member, the retaining member having

means to close over the ball of the forceps to hold the said ball and the forceps in movable connected relation to the rest.

In testimony whereof I have hereunto set 15 my hand in presence of two subscribing witnesses.

JOSEPH FRANKLYN TURNER.
